UNITED STATES PATENT OFFICE

PHILIP MOSKOVITZ AND SOPHIA MOSKOVITZ, OF PHILADELPHIA, PENNSYLVANIA

HAIR WAVER

Application filed June 18, 1929. Serial No. 371,886.

Our invention relates to a new and useful improvement in hair wavers and particularly to the type of hair waver which is adapted to produce the waved effect in the hair by retaining dampened hair properly clamped until the hair has dried and set, and without the application of any heat.

For the purpose of illustrating our invention, we have shown in the accompanying drawings forms thereof which are at present preferred by us since they will give in practice satisfactory and reliable results, although it is to be understood that the various instrumentalities of which our invention consists can be variously and interchangeably arranged and organized and that our invention is not limited to the precise arrangement and organization of these instrumentalities as herein shown and described.

Figure 1 is a perspective view of one form of our invention in closed position. Figure 2 is a perspective view in open position. Figure 3 is a side view. Figure 4 is an overhead view. Figure 5 is a cross-section on dotted line 5—5 indicated in Figure 4.

Figure 6 is a perspective view of another form of the invention in closed position. Figure 7 is a perspective view in open position. Figure 8 is a side view. Figure 9 is an overhead view. Figure 10 is a cross-section on dotted line 10—10 indicated in Figure 9.

Figure 11 is a side view of another form of the invention in closed position showing the elimination of the hinge, with clasps on both ends,—instead of a clasp on one end and a hinge on the other end as indicated in the aforementioned drawings of the invention.

Referring to Figures 1, 2, 3, 4 and 5,—channel body 1 is longitudinally curved corresponding generally to the curvature of the side of the head, as shown particularly in Figure 3, and also curved transversely to a suitable depth as illustrated especially in Figure 5. Both sides of channel body 1 have the side edges 2 and 3 turned over to prevent any possible cutting of the hair, since this is where the hair is drawn tightly across. Ends 4 and 6 are tapered to facilitate the passing of the wavers through the hair.

Connected to channel body 1 at hinge 7 is a double spring wire member 8 whose free extremity is in the form of clasp 9.

In this embodiment of our invention the hair is laid flat across the entire waver and wire member 8 is then deflected and forced tightly into the channel body by means of clasp 9, thereby depressing the hair into a wave. As many wavers as required are set in parallel relation to one another to produce a series of waves on the head.

Figures 6, 7, 8, 9 and 10 illustrate another form of our invention. Channel body 11 has a turned over perimeter, in lieu of turned over sides 2 and 3 as shown in Figures 1, 2, 3, 4 and 5. A resilient retainer band 13 is substituted for double spring wire 8.

Figure 11 represents another form of our invention. Both ends 16 and 17 of resilient retainer band 18 are free and are both similar in construction to clasp 15 in Figures 6, 7, 8, 9 and 10, thus eliminating hinge 14. Edge 19 is not turned over.

Having thus described our invention, what we claim as new and desire to secure by Letters Patent, is:—

1. A hair waver consisting of a channel-like body with tapering ends for receiving a strand of hair to be waved, the top of the walls of the said channel-like body being turned over and made flush with the outer face of the said walls providing a smooth, non-hair-cutting, rounded surface for the top of said walls, a double spring wire hingedly secured to one end of said channel-like body for movement into and out of said channel-like body for clamping the said strand of hair to be waved within the said channel-like body, the said double spring wire terminating in a resilient clasp for locking the said double spring wire in its operative position.

2. A hair waver consisting of a channel-like body with tapering ends for receiving a strand of hair to be waved, rounded, smooth, non-hair-cutting surfaces formed on the tops of the side walls of the said channel-like body, a double spring wire hingedly secured to one end of said channel-like body for movement into and out of said channel-like body for clamping the said strand of hair to be waved

within the said channel-like body, and a resilient clasp carried by the free end of the said double spring wire for locking the said double spring wire in its operative position.

- 5 3. A hair waver consisting of a channel-like body with tapering ends for receiving a strand of hair to be waved, rounded, smooth, non-hair-cutting surfaces formed on the tops of the side walls of the said channel-like body, a resilient hair retaining element hingedly secured to one end of the said channel-like body for movement into and out of the said channel-like body for clamping the strand of hair to be waved within the said channel-like body, and a resilient clasp carried by the free end of the said retaining element for locking the said retaining element in its operative position.

- 10 4. A hair waver consisting of a channel-like body with tapering ends for receiving a strand of hair to be waved, rounded, smooth, non-hair-cutting surfaces formed on the tops of the said walls of the said channel-like body, a double spring wire for clamping the said strand of hair within the said channel-like body, and resilient clasps formed on the ends of the said double spring wire, the said resilient clasps adapted to cooperate with the ends of the said channel-like member to lock the said double spring wire in its operative position.

- 15 5. A hair waver consisting of a channel-like body with tapering ends for receiving a strand of hair to be waved, a resilient hair retaining element for clamping the said strand of hair within the said channel-like body, and resilient clasps formed on the ends of the said retaining element, the said resilient clasps adapted to cooperate with the ends of the said channel-like member to lock the said resilient member in its operative position.
